AUTOMATIC WELL TEST SEAL

Rollie Lawrence Midgett, San Antonio, Tex.

Application December 6, 1939, Serial No. 307,910

5 Claims. (Cl. 166—10)

This invention relates to an improved automatic well test seal.

An object of the invention is to provide an automatic well test seal which will require neither the installation of well casing nor the removal of drill mud from the well hole, except at the strata being tested, for its proper operation.

A still further object of the invention is to provide an automatic well test seal which will be equally effective when sealing either a straight hole or one of irregular shape.

Another object of the invention is to provide a device of this class which automatically adjusts itself to well openings of different sizes.

Still another object of the invention is to provide a well test seal which will be safe, economical and highly efficient in use.

Another object of the invention is to provide an automatic well test seal employing an improved strainer which will be operative for preventing clogging of the suction or flow pipe.

And a still further object of the invention is to provide an automatic well test seal which, in a modified embodiment, will be operative for isolating a given strata within a well so that liquid may be forced into or removed from said strata.

In the drawings forming a part of my application,

Figure 1 is a side elevation of my device as it would appear in a well or test hole,

Figure 2 is an enlarged side elevation of my automatic well test seal, the view being partly broken away and shown in section,

Figure 3 is a vertical sectional view of the device,

Figure 4 is a vertical sectional view of the device as it would appear in operative position in a well or test hole, the flexible body employed being shown expanded into contacting engagement with the wall of the well or hole,

Figure 5 is a fragmentary top plan view, on a reduced scale, showing the device in the position assumed before expansion of the flexible sleeve,

Figure 6 is a transverse sectional view on the line 6—6 of Figure 4,

Figure 7 is a transverse sectional view on the line 7—7 of Figure 4,

Figure 8 is an enlarged detail sectional view of a portion of the strainer employed,

Figure 9 is a side elevation showing a slightly modified arrangement as it would appear in a well or test hole, and before expansion of the flexible sleeves employed, and

Figure 10 is a side elevation showing the arrangement of Figure 9 with the flexible sleeves expanded.

Referring now more particularly to the accompanying drawings, wherein like numerals of reference will be seen to designate like parts throughout the various views, the numeral 1 indicates a well or test hole which is of any suitable depth, it being understood, of course, that the hole is of sufficient depth to intersect a strata of oil, water or other liquid.

My improved automatic well test seal includes a body which is shown generally by the numeral 2. The body 2 includes a flexible sleeve 3 which is formed of rubber or other suitable material. As shown at 4, the sleeve 3 is reduced in thickness throughout its circumference medially of its length. Heads 5 and 6 normally close the body at its opposite ends, said heads being of substantially cylindrical shape and being enlarged at their corresponding inner ends, as shown at 7 and 8. As will be observed, the head 5 is formed with an eccentrically disposed port or bore 9 which is normally closed at its outer end by a plug 10. The head 5 is provided with an axial bore 11 which is threaded at its outer end to receive the lower end of a suction pipe 12. The inner end of the bore 11 is recessed and threaded to receive a hollow body member 13.

It will be seen in Figure 3 that the upper end of the sleeve 3 surrounds the flared portion 7 of the head. A ferrule 14 surrounds the upper end of the sleeve and retains said upper end of said sleeve in engagement with the outer face of said flared portion 7. A nut 15 is threaded on the outer half of the head 5 and engages the outer end of the ferrule 14. It will be seen that tightening of the nut 15 will shift the ferrule 14 inwardly, or downwardly, and thus clamp the upper end of the sleeve 3 tightly on the head 5. The head 6 is of somewhat similar construction to the head 5. However, said head differs in construction in that it includes a recess 16 in which is mounted a tubular seat 17, said seat surrounding the upper end of an axial bore 18 which extends throughout the length of the head 6. The lower or outer end of said bore 18 is recessed to receive a packing bushing 19. The flared portion 8 of the head 6 is engaged with the lower end of the flexible sleeve 3 and is held in engagement therewith by means of a ferrule 20 which surrounds said lower portion of said sleeve. The ferrule 20 is forced into tight engagement with the lower end of the sleeve by means of a nut 21 which is threaded on the lower end of

the head 6. The nut 21, as will be seen by referring to Figure 3, is recessed and internally threaded, at 22, to receive the upper end of a strainer pipe 23. It should be understood that the pipe 23 may be of any suitable length and may, if desired, comprise a number of lengths of pipe with the strainer portion located on the lower end. The body member 13 is threaded near its lower end, as shown at 24. Secured at said threaded portion 24 is a stop sleeve 25 which is formed with an annular stop shoulder 26. The purpose of the stop sleeve 25 and stop shoulder 26 will be made apparent hereinafter.

At its lower end, the body member 13 is internally threaded to receive a guide member 27, said guide member being of smaller diameter than the body member 13. The guide member 27 is threaded at its lower end and has screwed thereon the upper or inner end of a stop sleeve 28. The stop sleeve 28 includes a sleeve portion 29 which is slidably engaged in the bore 18. The stop sleeve 28 includes a lower portion 30 and a stop shoulder 31, said stop shoulder being, in operative position, in engagement with the packing bushing 19. The stop sleeve 28 is hollow throughout its length and cooperates with the guide member 27 and body member 13 for providing a continuation of the suction pipe 12. The lower end of the portion 31 is internally threaded to receive a lower section 32 of the suction pipe which lower section extends downwardly into the strainer pipe 23. As will be seen, the guide member 27 is of less diameter than either the sleeve 28 or the member 13. The purpose of this construction will be brought out during the course of the following description. It is also desired to point out that the lower end surface of the body member 13 and the upper end of the outer surface of the sleeve portion 29 of the stop sleeve 28 are tapered to define guide surfaces.

As seen in Figure 4, the strainer pipe 23 is provided with a guide bushing 33 which is lined with a resilient facing 34 to confront the section 32 of the suction pipe and thus provide centering means for said pipe within the strainer pipe 23. A spider 35 axially mounts the bushing 33 within said pipe 23.

Referring now to Figures 4 and 8 of the drawings, wherein the strainer pipe construction is shown in detail, it will be seen that said strainer pipe is formed by striking in end portions of said pipe to define inwardly disposed lips 36 and strainer openings 37. The strainer openings are formed in staggered relation to each other about the area of the pipe. The strainer pipe of my invention effectually prevents clogging of the suction pipe, avoiding consequent impedance to continuous flow.

In use, when the device is being installed in a well, the weight of the suction pipe and the strainer pipe will cause the sleeve 3 to be extended to its full length, as shown in Figures 1, 2 and 3 of the drawings. In this position, the head 6 is held in its lowermost engagement with the packing bushing 19 in engagement with the shoulder 31 of the stop sleeve. In order to prevent collapse of the sleeve 3, water is poured therein through the opening 9, the plug 10, of course, having first been removed and, after the space between the sleeve and body member has been filled with water, said plug 10 is replaced. When the device has been inserted in the well or test hole to the extent that the lower end of the strainer pipe 23 is in contacting engagement

with the bottom of said well, supporting effort is removed from the portion of the suction pipe 12 above the body. When this is done, the weight of the suction pipe 12 will bear against the body and will force the head 6, the body member 13, the guide member 27, and the stop sleeve 28, with the pipe 32 thereon, downwardly. The head 6 will be displaced from about the sleeve portion 29 of the stop sleeve 28. As this is done, the bore 18 will clear the upper end of the sleeve portion 29 so that a passage will be defined between the surface of the bore and the outer surface of the guide member 27. Water or other liquid will be permitted to pass through this passage in either direction so that free movement of the flexible sleeve 3 will be permitted. As the head 6, with the body member, guide member and stop sleeve thereon, move downwardly, the head 6 will remain stationary and will cause the sleeve 3 to expand to the position shown in Figure 4. That is to say, the flexible sleeve 3 will be expanded so that its outermost circumferential portion will contact the surface of the well or test hole. As the lower end of the body member 13 engages in the tubular seat 17 located in the recess 16 of the axial bore 18, the water passage from the inside of the flexible sleeve 3 is closed. Further downward movement of the head 6 and the body 13 and the sleeve 25, by weight of the drill stem or of applied pressure, causes a hydraulic pressure inside of the flexible sleeve 31, expanding the seal firmly against the inside of the well. When the annular stop shoulder 26 engages with the seat 17, a doubly secure seal is effected and the excess weight of the drill stem rests on the sleeve 25 and the head 6. Liquid beneath the sleeve may then be drawn upwardly through the strainer pipe and suction pipe to the top of the well where it may be inspected for quality and, in addition, an estimate may be made as to the probable capacity of the strata in which the pipe 23 is resting.

When removing the device from the well after a testing operation, upward pressure is exerted on the suction pipe. When this is done, the stop shoulder 31 on the sleeve 30 will limit upward movement of the body 1 and, when the packing bushing 19 engages the stop shoulder 31, liquid within the sleeve 3 will be retained in the sleeve 3 with said sleeve in a contracted position to facilitate extracting the seal from the well or test hole.

It is desired to call attention to the fact that the sleeve, being of flexible construction, will adjust itself to engage test holes having straight side walls or walls of irregular contour. Also it is desired particularly to point out that the expansion and contraction is automatic, being effected by resting the weight of the drill stem on the head of the seal while the strainer pipe is resting on the bottom of the well, or by releasing the pressure by lifting the pressure from the seal. In view of the fact that the mid-portion of the flexible sleeve is reduced in thickness, as shown at 4, said mid-portion will expand first, with the result that uniform expansion of the sleeve above and below said reduced portion will be assured.

It is also desired to call attention to the fact that the use of my improved seal permits circulation of mud for flooding strata tested before removing the seal, and also the circulation of mud to float sediment that might bind against the strainer pipe or above the seal while being extracted from the test hole.

Referring now to the embodiment of the invention shown in Figures 9 and 10, the numeral 38 indicates a well of any depth. Strata which is desired to be isolated is shown generally at 39. In this embodiment of the invention, two of my improved seals are connected in tandem; that is to say, one above the other in spaced relation. The seals are indicated by the numerals 40 and 41 and are each of identical construction to that described with reference to Figures 1 to 8. The seals 40 and 41 are connected by a pipe 42 and a pipe 43, said pipe 43 having holes 44 therein. A pipe 45 extends from the lower end of the seal 41 to the bottom of the well, said pipe being of any determinate length. It is to be noted that no strainer pipe is employed with this embodiment of the invention. If it is desired to seal the strata 39 or to remove liquid therefrom, it is only necessary to remove lifting pressure from the suction pipe 46, which supports both of the seals in the well, when the sleeves of the seals will expand to the position shown in Figure 10 of the drawings. After this has taken place, liquid may be forced through the openings 44 from the pipe 42 and into the strata 39. If it is desired to remove liquid from the strata 39, without disturbing the rest of the well, said liquid is forced outwardly through the openings 44, the pipe 42 and the pipe 46. It will be understood that the strata may be located at any point in the wall. This embodiment of my invention may be employed for readily locating leaks in the casing of a finished well or for the purpose of isolating a single strata at any depth. Also, when coupled in series (i. e. one above the other), the seals will be effective for isolating a single strata at any depth.

Having thus described the invention, what is claimed as new is:

1. In an automatic well test seal, a body including heads, one of said heads having a body member, a guide member carried by the body member, a stop sleeve carried by the body member, a stop sleeve carried by the guide member, said last-mentioned stop sleeve receiving the other of said heads in slidable engagement therewith, and a flexible sleeve extending about the body member, the guide member and first-mentioned stop sleeve and being secured to each of said heads, said flexible sleeve and said first-mentioned head being shiftable downwardly for expanding the flexible sleeve to contact the inner surface of a well for sealing said well, said second-mentioned head engaging the first-mentioned stop sleeve when the flexible sleeve is in expanded position.

2. In a device of the class described, a body including a flexible sleeve, heads closing the flexible sleeve at its opposite ends, said body having a body member therein and connected to one of the heads, a guide member connected with the body member, and a stop sleeve connected with the guide member, said stop sleeve having a sleeve portion slidably engageable in a bore in the other of said heads, a suction pipe connected with the first-mentioned head, and a strainer pipe connected with the other of said heads, said first-mentioned head, body portion, guide member and stop sleeve being shiftable by the weight of the suction pipe for displacing the stop sleeve from the section-mentioned head and causing the flexible sleeve to expand to engage the sur-

face of a well for sealing the well, said guide member defining a passage for liquid to and from the interior of the flexible sleeve.

3. In an automatic well test seal, a flexible sleeve, upper and lower heads connected with the sleeve at its opposite ends, means connecting the heads with the sleeve, said upper head being formed with an opening for admitting liquid to the interior of the sleeve, the other of said heads being formed with a bore, a guide member carried by the upper head, a stop sleeve on the body member, a guide member carried by the body member and being of less diameter than said body member, a stop sleeve carried by the guide member and having a sleeve portion normally disposed in the bore of the lower head, a suction pipe connected with the upper head, and a strainer pipe connected with the lower head, said strainer pipe being normally engageable with the bottom of a well, said upper head, body member, guide member, and second-mentioned stop sleeve being movable upon release of supporting effort from the suction pipe whereby said second-mentioned stop sleeve will be disposed from the bore in the second-mentioned head and the first-mentioned stop sleeve will be shifted to engage the inner surface of said head, said flexible sleeve being simultaneously expanded to contact the surface of a well for sealing said well.

4. In a device of the class described, a body including a flexible sleeve, heads closing the body at its opposite ends, one of said heads having means for permitting entry of liquid to within the flexible sleeve, a suction pipe connected with one of said heads, a strainer pipe connected with the other of said heads, and means defining a passage for liquid from the flexible sleeve, said first-mentioned head being shiftable for expanding the flexible sleeve into contacting engagement with the wall of a well for sealing said well.

5. In a device of the class described, a flexible sleeve, heads closing the flexible sleeve at its upper and lower ends, a suction pipe connected with the upper head, a strainer pipe connected with the lower head, a body member carried by the upper head, said upper head having an opening to permit flow of liquid to within the flexible sleeve, a stop sleeve on the body member, a guide sleeve on the body member, said lower head having a bore and said bore being recessed at its opposite ends, a tubular seat on the upper end of said bore, a packing bushing on the lower end of said bore, said guide member being of less diameter than the body member and cooperating with the bore in the lower head to define a liquid passage to and from the interior of the flexible sleeve, and a stop sleeve carried at the lower end of the guide sleeve and including a sleeve portion and a stop shoulder, said sleeve portion of the stop sleeve receiving the bore of the lower head when the flexible sleeve is in retracted position, said upper head, body member, guide member and second mentioned stop sleeve being shiftable for displacing the lower head from the sleeve portion of the second mentioned stop sleeve and moving said bore into engagement with the first mentioned stop sleeve about the lower end of the body member, said flexible sleeve being simultaneously expanded to contact the wall of a well for sealing the well.

ROLIE LAWRENCE MIDGETT.
